UNITED STATES PATENT OFFICE

CLAYTON L. DAY, OF NEW YORK, N. Y., AND LEWIS McDONALD, OF CHICAGO, ILLINOIS,
ASSIGNORS TO CHICAGO BRIDGE & IRON CO., A CORPORATION OF ILLINOIS

CONTAINER FOR GASES AND VOLATILE LIQUIDS

Application filed December 27, 1927. Serial No. 242,326.

This invention relates to improvements in containers for gases and volatile liquids, and more especially to such a container adapted to hold the contents under pressure.

5 One of the features of our invention is the provision of such a container with a substantially flat roof and means to counterbalance or counteract the normal internal pressure tending to lift or distort the roof.

10 Another feature of the invention is a provision for automatic means for relieving the internal gas pressure, said means operating when the pressure exceeds the weight of the counterbalance. In other words, the head 15 of liquid on the roof used as a counterbalance, and internal gas pressure are automatically balanced.

Other features and advantages of our invention will appear more fully as we proceed with our specification.

In that form of device embodying the features of our invention shown in the accompanying drawings, Figure 1 is a vertical sectional view, and Fig. 2 is a top plan view 25 with a part of the top broken away.

As shown in the drawings, 10 indicates the usual cylindrical shell or wall of a tank and 11 the bottom.

12 indicates a flat roof, and the upper edge 30 of the shell 10 is extended above the level of the roof as indicated by 10^a to form a reservoir on top of the roof 12 for holding the liquid 13 to serve as a counterbalance against normal internal gas pressure inside of the 35 tank. The liquid 13 may, for example, be water in warm climates or brine in colder ones.

It will be seen that, in order to prevent distortion of the roof 12, the internal gas 40 pressure must never exceed the counterbalance afforded by the liquid 13 on top of the roof. It may not be possible or practicable always to maintain the same head of liquid on the roof. Consequently the venting 45 means must be designed to operate at different gas pressures corresponding to different heads of liquid on the roof. This is accomplished by providing a vent pipe 14 having one end 14^a in communication with the interior of the container. Such pipe ex-

tends upwardly above the level of the liquid 13 and then is bent downwardly so that its other end 14^b is immersed in the liquid 13. There is preferably provided a cup 15 in the roof and the end 14^b of the vent pipe dips 55 into this cup. It will be seen that by this communication the vent pipe 14 is sealed by the head of liquid 13 on the roof and that the pressure held will vary with such head. In other words, as the amount of liquid 13 60 on top of the roof is decreased, the highest possible pressure held inside of the tank is accordingly decreased. By providing the cup 15 and extending the end 14^b of the pipe 14 into the cup, the weight of the material 65 in the roof itself can be operatively included as part of the counterbalancing weight and also the rafters or framing if attached to the roof.

The rafters or framing just referred to 70 may include the rafters 16 suitably supported on posts 17 and, if desired, the rafters may be attached to the roof 12 and will then not only support the roof and water when there is no internal gas pressure, but will 75 also assist the weight of the water in counterbalancing internal gas pressure thus permitting the use of less water.

18 indicates a vacuum relief of any usual construction that may be employed, if desired, to relieve undue vacuum.

While we have shown and described certain embodiments of our invention, it is to be understood that it is capable of many modifications. Changes, therefore, in the 85 construction and arrangement may be made without departing from the spirit and scope of the invention disclosed in the appended claims, in which it is our intention to claim all novelty in our invention as broadly as 90 possible in view of the prior art.

What we claim is new, and desire to secure by Letters Patent, is:

1. A container adapted to hold a gas or volatile liquid under pressure having a substantially flat roof; a liquid on the roof, the weight of said liquid operating to counterbalance the internal gas pressure against said roof; a cup depressed in said roof, said cup also being filled with said liquid on said 100

roof; and automatic means for relieving the internal gas pressure when the same exceeds the counterbalancing effect of the liquid, said means including a vent pipe having one end 5 in communication with the interior of the container, said vent pipe extending upwardly above the level of the liquid on the roof, and then bent downwardly with its other end immersed in the liquid in the cup in 10 the roof.

2. A container adapted to hold a gas or volatile liquid under pressure having a substantially flat stationary roof, said roof adapted to hold liquid thereon variable in 15 amount, the weight of said liquid operating to counterbalance the internal gas pressure against said roof; and means for automatically relieving the internal gas pressure when the same exceeds the counterbalancing 20 effect of said liquid, regardless of the amount of liquid on the roof.

3. A container adapted to hold a gas or volatile liquid under pressure having a substantially flat stationary roof, said roof 25 adapted to hold liquid thereon variable in amount, the weight of said liquid operating to counterbalance the internal gas pressure against said roof; and means for automatically relieving the internal gas pressure 30 when the same exceeds the counterbalancing effect of said liquid, regardless of the amount of liquid on the roof, said means including a vent pipe having one end in communication with the interior of the container, said vent pipe extending upwardly 35 above the level of the liquid on the roof, and then bent downwardly with its other end immersed in said liquid.

In witness whereof, we have hereunto set 40 our hands and affixed our seals, this 12th day of December, 1927.

CLAYTON L. DAY.
LEWIS McDONALD.
